UNITED STATES PATENT OFFICE.

LOUIS KAN AND FLOYD J. WILSON, OF WALLA WALLA, WASHINGTON.

SHOCK-ABSORBING HINGE.

Application filed January 26, 1927. Serial No. 163,637.

This invention relates to shock-absorbing hinges and has as one of its objects to provide a hinge that will absorb the shock of closing a spring actuated closure.

Another object of the invention is to provide a shock-absorbing hinge that may be adjusted without removal from the closure.

A further object of the invention is to provide a shock-absorbing hinge that is cheap to manufacture, requiring a small number of parts only, of standard manufacture.

With these and other objects in view, reference is had to the accompanying drawings in which

Fig. 1 is a side elevation of a spring hinge showing the application of the shock-absorber;

Fig. 2 is a back view thereof;

Fig. 3 is a front view of one plate of said hinge;

Fig. 4 is a back view of one plate of the hinge;

Fig. 5 is a sectional elevation of the hinge;

Fig. 6 shows a front view of one of the clips before crimping;

Fig. 7 is a similar view to Fig. 6 after crimping;

Fig. 8 is a cross section of one plate of the hinge showing the upright clips;

Fig. 9 shows a front view of the adjusting tit; and

Fig. 10 is a side elevation of the bumper pin.

Having reference to the drawings, like numerals refer to like parts throughout the several views and the numeral 1 refers to a hinge, of the usual single-acting spring-hinge type, and comprising a male plate 2 and a female plate 3, both of which having upturned ends or raised portions 4 in which a pin 5, pivotally joining the two parts, is secured in an elevated position by riveting on the ends in the usual manner of such construction, this position of the upturned ends providing lever arms fulcrumed on said hinge pins and having one arm perpendicular to said plates.

In such a hinge a spring 6 is usually positioned about the pin with one of its ends pressing against the female plate and the other end pressing against the male plate, the spring being adapted to open the hinge which movement closes the door to which it is attached.

While a spring hinge is shown herein it will become evident that hinges other than spring hinges may have the device attached

thereto in which case any other means may be employed to close the door, as a weight or a spring attached to the door and casing.

Where a spring hinge is used a barrel 7 may enclose the spring, in which case a slot 8 will be cut therein to provide for the device, which will now be explained.

Attached to, or made a part of the hinge, is the shock-absorber 9 consisting of an outer 65 upturned tit 10 formed from the outer edge 11 of one of the plates, an adjusting tit 12 stamped from the metal of the plate, and an inner upturned tit 13 formed on the inner edge 14 of the plate. The tits are formed 70 integral with the plate and are positioned in line and are provided with an aligned set of slot 15 the tits and their slots forming raised supports in which is slidably mounted, in parallel relation to the plate, a bumper pin 16. 75

The bumper pin is threaded part way to provide for a nut 17 for adjustment purposes, the nut normally resting against the adjusting tit 12 and held thereagainst by a spring 18 interposed between the nut and the outer 80 upturned tit.

The pin has a rounded bumper head 19 on one end and is slotted at the other end to receive a screw-driver by which the bumper head may be advanced or retracted by rotating the pin in the nut.

Now the outer and inner tits are slotted to provide relatively long prongs 20 and the pin is slidably secured in the slots by bending the prongs partly over the pin, as illustrated in 90 Fig. 7. The adjusting tit has shorter prongs, as shown in Figs. 8 and 9, for it is obvious that the outer and inner tits will hold the pin in place when bent as aforesaid.

The bumper head is positioned to register 95 with the inner edge 21 of the second plate 2, which provides a bumper, as the hinge approaches the maximum opening point so that to complete the opening (the opening of the hinge being the equivalent of closing the 100 door) the pin will be driven outward by engagement with the bumper and the movement of the lever arms about the hinge pin, the nut then acting against the resistance of the spring to act as a cushion and prevent the 105 door slamming.

By the above arrangement the bumper is exposed on top of the plate, and the adjusting means, formed integral with the pin, is likewise exposed for accessibility.

In use the hinge is attached to a door and casing in the usual manner, as by screws and,

if a plain hinge is used, a spring will be attached to the door to maintain it in the closed position, or if a spring hinge is used the spring of the hinge will close the door.

5 Now with the door open the spring 6 will be under its greatest tension when it will have a tendency to cause the door to slam shut upon being released.

With this device incorporated in a hinge, 10 when the door has nearly completed its closing movement, the edge, or bumper, of one plate of the hinge will strike the bumper head, as a result of the lever above mentioned, when, the bumper pin being yieldingly mounted, the pin will yield and will thus cause the door to slow up its rapid movement and finally come to rest without shock.

In case the weight of the doors vary, or a 15 spring is stiffer in one hinge than in the other, adjustment may be accomplished by 20 a screw-driver without removing the hinge from the door, the threaded and exposed bumper pin making for precise convenient adjustment of the bumper.

The word "hinge" is used herewith to differentiate between a hinge applicable to the surface, and having its surface exposed, and a "butt" adapted to be secured to the edge of a door, to be more or less concealed.

Having thus described our invention, we 25 claim

In a shock absorbing hinge, the combination of a hinge comprising plates, having upturned ends pivotally joined together, lever arms formed by said upturned ends, a bumper provided by the inner edge of one of said plates, raised supports formed integral with the other of said plate, a bumper pin slidably and yieldingly mounted in said supports to register with said bumper, for operation by the movement of said lever arms, and an exposed adjusting means positioned and adapted to adjust the tension on the bumper pin without removing said hinge.

40 In testimony whereof we affix our signatures.

LOUIS KAN.
FLOYD J. WILSON.
